UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

SHUTTLE FEELER MECHANISM FOR LOOMS.

Application filed April 8, 1925. Serial No. 21,683.

To all whom it may concern:

Be it known that I, MELVIN L. STONE, a citizen of the United States, and a resident of Lawrence, in the county of Essex and State of Massachusetts, have invented an Improvement in Shuttle Feeler Mechanisms for Looms, of which the following description, in connection with the accompanying drawings, is a specification, like characters on the drawings representing like parts.

This invention relates to filling replenishing looms wherein the filling is replenished from time to time.

In that class of filling replenishing mechanisms wherein the shuttle is provided with a fresh supply of filling when that in the shuttle has become substantially exhausted, it will be manifest that if the shuttle is not in proper replenishing position, the transfer 20 of a supply of filling thereto is liable to be accompanied by injury to the transferring mechanism, or the shuttle, or both, so that the parts are sometimes seriously damaged.

In looms now in ordinary use it is common to provide a shuttle feeler which, upon call for replenishment of filling, is moved into a backward feeling position to feel for the shuttle, and if the shuttle is not fully in the box, to prevent actuation of the replenishing mechanism. In other cases, means have been provided to prevent the operation of the replenishing mechanism if the shuttle is not fully boxed or has entered the box too far as by reason of a worn picker.

The present invention is directed to a further simplified development of means for preventing the actuation of the replenishing mechanism when the shuttle is either too far in the box or has not been fully boxed, and an important feature of the present invention consists in means mounted on the lay for cooperating with the usual feeler slot of the shuttle to determine whether or not the shuttle is properly boxed, and upon detection of an improperly boxed shuttle to prevent actuation of the replenishing mechanism. Looms of the replenishing type employ shuttles which are provided with a slot in the side wall for the entrance of the feeler to detect the condition of the filling, and when the filling is substantially exhausted the feeler initiates replenishment of filling and effects such replenishment when the shuttle reaches the replenishing side of the loom. The present invention utilizes the usual

feeler slot of the shuttle to determine whether or not the shuttle is in proper position in the box, and upon detection of an improperly boxed shuttle to suspend the operation of the replenishing mechanism.

The invention and novel combination of parts will best be made clear from the following description and the accompanying drawings of one good form thereof.

In the drawings:

Fig. 1 is a perspective view of a loom at the filling replenishing side thereof;

Fig. 2 is a cross-sectional view through the lay and shuttle box, showing the action of the parts when the shuttle is properly 70 boxed on call for replenishment of filling;

Fig. 3 is a view similar to that of Fig. 2, but showing the relation of parts when the detector finds the shuttle improperly boxed, that is, either too far in or too far out of the 75 shuttle box; and

Fig. 4 is an enlarged perspective detail showing more particularly the shuttle detector and its associated parts.

The loom frame 1 has mounted thereon as usual the transverse or rock shaft 2 supported in suitable bearings 3, one at each side of the loom, and secured to and extending rearwardly from the rock shaft 2 is an arm 4, the bifurcated rear end portion of which embraces a pin 5 extending from a detector governor 6 pivotally mounted at 7 on a bracket 8 extending from the loom frame, the construction being such that upon call for replenishment of filling the transverse 90 or rock shaft 2 will be rocked, as usual in this class of looms, under the dictates of the filling feeler at the opposite side of the loom to effect replenishment of filling, and perforce, in the present invention, move the detector governor 6 rearwardly.

The filling hopper 9 is herein shown as of the rotary type and contains a number of bobbins supplied with filling, as at 10, and pivotally supported upon the stud shaft 11 100 is the transerrer 12 having a downwardly extending arm 13 to which is pivoted at 14 the usual dog 15 for causing actuation of the transerrer by engagement with a bunter 16 on the lay when filling is to be replenished.

Extending from the detector governor 6 is a slotted arm 17 which is engaged by a pin 18 carried by the dog 15, the construction being such that upon call for replenishment of filling the detector governor 6 will 110

be moved rearwardly through the connections with the transverse or rock shaft and position the dog 15 for engagement by the bunter 16 provided the shuttle is properly boxed. With the exception of the construction and operation of the detector governor 6, the mechanism so far described may be substantially as now common in the commercial loom.

10 The lay 19 at the replenishing side of the loom has the usual shuttle box 20 provided with an opening 21 in its bottom for the ejection of a spent filling carrier when the shuttle 22 is properly positioned in the 15 replenishing box for the transfer and a side opening in its front wall.

Mounted on the lay, preferably below the front wall of the replenishing shuttle box is a detector shaft 23 which may be conveniently supported in bearings 24 carried by the lay, and secured to the detector shaft 23 are the detector fingers 25 and 26 adapted to cooperate with the feeler slot 27 of the shuttle 22 when the detector shaft is rocked to detect the position of the shuttle in the shuttle box.

The detector shaft 23 is normally under the influence of a spring tending to hold the detector fingers 25 and 26 in a frontward position relative to the shuttle box, and in the present instance of the invention the spring 29, Fig. 4, is mounted upon the detector shaft 23, one end of the spring being secured to a collar 30 on the detector shaft and the other end of the spring being secured at 31 to one of the bearings 24, as indicated in Fig. 4, the normal tendency of the spring acting to turn the detector shaft 23 in a frontward or counterclockwise direction, viewing Figs. 2 and 3. To limit the frontward swinging movement of the detector fingers under the impulse of the spring 29, a stop is provided for controlling the rocking movement frontwardly of the detector shaft, and in the present instance such stop is devised as a shoulder 32 on one of the brackets 24 which cooperates with a shoulder 33 extending from a collar 34 secured to the detector shaft.

50 The detector fingers 25 and 26, as hereinbefore described, are secured to the detector shaft, and as shown, each detector finger is carried by a sleeve or collar 35 and may be secured thereto by the set screw 36. Interposed between the detector shaft 23 and the sleeves or collars 35 is an elongated sleeve 37 which may be adjustably secured to the detector shaft 23 by a set screw 38 whereby the detector fingers may be adjusted relatively in unison with relation to the shaft 23. Inasmuch as it is sometimes desirable to adjust the detector fingers individually or separately, each of the collars 35 is secured to the elongated sleeve 37 by a set screw 39.

The detector shaft 23 carries at its inner end an upstanding projection or finger 40, and should such finger be pushed rearwardly on call for replenishment of filling, it will turn the detector shaft 23 to carry the 70 detector fingers inwardly towards the shuttle in the replenishing box. The upstanding finger may be secured to the detector shaft 23 adjustably by means of the set screws 41 to permit proper relative adjustment of 75 parts to effect the desired cooperative relation.

The detector governor 6 has adjustably mounted thereon the contacting member 42 which is shown as secured to the detector governor by a bolt 43 which passes through a slot 44 in the contact member 42, and at the rearward portion the contact member has a laterally extending end 45 which, when the detector governor is moved to a rearward position on call for replenishment of filling, will contact with the upstanding arm or projection 40 on the detector shaft and, perforce, move the detector fingers towards the shuttle in the replenishing box. Should the shuttle 28 be properly positioned in the replenishing box for the transfer, both of the detector fingers 25 and 26 will enter the feeler slot 24 in the shuttle and permit rocking movement of the detector shaft 23, and simultaneously therewith, the detector governor will be moved rearwardly to a sufficient extent to position the dog 15 for engagement with the bunter 16 on the lay and filling replenishment will be effected.

Should the shuttle, however, not be properly boxed, one of the detector fingers 25 or 26 will engage the wall of the improperly boxed shuttle and prevent rocking movement of the detector shaft 23, and, perforce, limit the rearward movement of the detector governor 6, so that the dog 15 will not be positioned for engagement by the bunter 16 on the lay and filling replenishment will be suspended.

More particularly, should the shuttle 28 fail to enter the shuttle box sufficiently for a proper transfer of the filling carrier thereto, the detector finger 25 will engage the wall of the shuttle, as indicated in Fig. 1, and thereby limit the movement of the detector shaft and the detector governor so that the dog 15 will not be operatively related to the bunter 16 and filling replenishment will not be effected. On the other hand, should the shuttle be too far in the box, which may occur at times owing to a worn picker, the detector finger 26 will engage the wall of the shuttle at the inner end of the detector slot and likewise prevent turning movement of the detector shaft and detector governor to prevent actuation of the replenishing mechanism.

Inasmuch as the detector fingers should

not enter the feeler slot sufficiently far to interfere with the incoming filling carrier on replenishment of filling, means are herein provided in accordance with the present invention to limit the inward swinging movement of the detector fingers. As shown, such limitation of movement is effected by means of a pin 46 mounted on an adjustable collar 47 secured to the detector shaft 23 and positioned to contact with the front surface of the bearing 24 when the detector shaft is turned clockwise as indicated in Fig. 2.

From the construction shown as one good practical form of the present invention, it will be apparent that filling replenishment will be suspended or prevented should the shuttle be either too far in or too far out of the replenishing box on call for replenishment of filling, and such control of the operation of the replenishing mechanism or transerrer is effected by a feeler member which cooperates with the usual feeder slot of the shuttle, either to permit replenishment of filling should the shuttle be properly boxed or prevent such replenishment of filling should the shuttle be improperly boxed.

What is claimed is:

1. In a filling replenishing loom, the combination of the transerrer, the transfer dog, a shuttle having a feeler slot, detector means on the lay at the replenishing side cooperating with the feeler slot of the shuttle for determining the position of the shuttle, and connections between said detector means and dog for rendering the dog inoperative unless said detector means enters the feeler slot on call for replenishment of filling.

2. In a filling replenishing loom, the combination of the lay having a shuttle box provided with a slot in its front wall to register with the feeler slot in the shuttle, a shuttle detector, a detector governor normally in an inoperative front position and moved rearwardly to an operative position on call for replenishment of filling, means connected with the detector constructed and arranged to be engaged by the detector governor when in rearward operative position to cause the detector to feel through the slot in the front wall of the shuttle and enter the feeler slot when the shuttle is properly positioned in the shuttle box, and means controlled by the detector governor to prevent replenishment of filling should the detector not enter the feeler slot of the shuttle.

3. In a filling replenishing loom, the combination of the lay, a shuttle having a feeler slot, a shuttle detector mounted on the lay, and means for causing the shuttle detector to feel for the feeler slot of the shuttle on call for replenishment of filling and prevent such replenishment should the detector not enter the feeler slot of the shuttle.

4. In a filling replenishing loom, the combination of the lay, a shuttle having a feeler slot in its side walls, a shuttle detector mounted to enter the feeler slot in the side wall of the shuttle, and a detector governor for causing the shuttle detector to feel for the feeler slot of the shuttle on call for replenishment of filling and prevent operation of the replenishing mechanism should the detector not enter the feeler slot of the shuttle.

5. In a filling replenishing loom, the combination of the lay, a shuttle having a feeler slot, two shuttle detectors mounted for cooperation with the feeler slot, and means for causing the detectors to feel for the feeler slot of the shuttle on call for replenishment of filling and acting to prevent replenishment should either of the detectors fail to enter the feeler slot of the shuttle.

6. In a filling replenishing loom, the combination of the lay, a shuttle having a feeler slot, a shuttle detector mounted for cooperation with the feeler slot, a detector governor positioned on call for replenishment of filling to cause the shuttle detector to move towards the shuttle and feel for the feeler slot, means connected to the detector for preventing full operative movement of the detector governor should the detector not enter the feeler slot as the lay advances, and means controlled by the governor to prevent replenishment of filling should the detector not enter the feeler slot.

7. In a filling replenishing loom, the combination of the lay, a shuttle having a feeler slot, a shuttle detector mounted on the lay for cooperation with the feeler slot, a detector governor positioned on call for replenishment of filling to cause the shuttle detector to move towards the shuttle and itself moved by the detector should the detector not enter the feeler slot as the lay advances, and means controlled by the governor to prevent replenishment of filling should the detector not enter the feeler slot.

8. In a filling replenishing loom, the combination of the lay, a shuttle having a feeler slot, a shuttle detector mounted on the lay, a detector governor moved rearwardly on call for replenishment of filling and acting at such times to move the shuttle detector towards the shuttle to feel for the feeler slot, a transerrer, and connections between the transerrer and governor to prevent operation of the transerrer should the shuttle detector fail to enter the feeler slot of the shuttle.

9. In a filling replenishing loom, the combination of the lay having a shuttle box provided with a slot in its front wall to register with the feeler slot in the shuttle, a shuttle detector comprising two fingers, a detector governor normally in an inoperative front position and moved rearwardly to an opera-

tive position on call for replenishment of filling, means connected with the detector constructed and arranged to be engaged by the detector governor when in rearward operative position to cause the detector fingers to feel through the slot in the front wall of the shuttle and enter the feeler slot when the shuttle is properly positioned in the shuttle box, and means controlled by the detector governor to prevent replenishment of filling should the detector fingers not enter the feeler slot of the shuttle.

10. A shuttle detector for looms, comprising a detector shaft mounted on the lay and having a detector to cooperate with the feeler slot of a shuttle, a detector governor for moving the detector towards the shuttle on call for replenishment of filling, and means controlled by the detector governor to prevent replenishment of the filling should the detector fail to enter the feeler slot of the shuttle.

11. A shuttle detector for looms, comprising a detector shaft mounted on the lay and having a detector to cooperate with the feeler slot of a shuttle, a detector governor for moving the detector towards the shuttle on call for replenishment of filling, means controlled by the detector governor to prevent replenishment of the filling should the detector fail to enter the feeler slot of the shuttle, and stops for limiting the movement of the shuttle detector.

12. In a filling replenishing loom, the combination of a transerrer, a transerrer dog, a detector governor controlling the position of the dog on call for replenishment of filling, a detector actuated by the detector governor to feel for the feeler slot of a shuttle on call for replenishment of filling

and to contact with the shuttle at either end of the feeler slot to prevent replenishment of filling when the shuttle is improperly boxed.

13. In a filling replenishing loom, the combination of the lay having a shuttle box at the replenishing side provided with an opening in its front wall to register with the feeler slot of the shuttle when properly positioned for replenishment of filling, a shuttle detector mounted to enter the opening and feeler slot of the shuttle on call for replenishment of filling, a detector governor which is moved on call for replenishment of filling to effect movement of the shuttle detector, and means controlled by the detector governor to prevent replenishment of filling should the detector fail to enter the feeler slot of the shuttle.

14. In a filling replenishing loom, the combination of the lay having a shuttle box at the replenishing side provided with an opening in its front wall to register with the feeler slot of the shuttle when properly positioned for replenishment of filling, a shuttle detector mounted to enter the opening and feeler slot of the shuttle on call for replenishment of filling, a detector governor which is moved on call for replenishment of filling to effect movement of the shuttle detector, a stop to limit the extent of movement of the shuttle detector into the feeler slot of the shuttle, and means controlled by the detector governor to prevent replenishment of filling should the detector fail to enter the feeler slot of the shuttle.

In testimony whereof, I have signed my name to this specification.

MELVIN L. STONE.
